United States Patent Office.

CHARLES KALBFUSS, OF NEW RICHMOND, OHIO.

Letters Patent No. 67,769, dated August 13, 1867.

WARMING APPARATUS FOR FIRE-PLACES.

The Schedule referred to in these Letters Patent and making part of the same.

TO WHOM IT MAY CONCERN:

Be it known that I, CHARLES KALBFUSS, of New Richmond, Clermont county, Ohio, have invented a new and useful Warming and Ventilating Apparatus; and I hereby declare the following to be a full, clear, and exact description thereof, reference being had to the accompanying drawings, making part of this specification.

My invention relates to that class of heating apparatus which is located in the chimney, immediately over the fire in a grate, for the purpose of warming air by means of the fire and smoke which ascend within the chimney, and my improvement consists in such a construction of apparatus as will give out the greatest amount of warm air with the least consumption of fuel. In the accompanying drawings—

Figure 1 is a transverse section of a grate provided with my improved warming and ventilating apparatus; and

Figure 2 is a perspective view of the apparatus detached from the grate, a portion of one side being broken away, so as to exhibit the internal construction.

A represents the fire-basket or grate, and placed immediately over this basket is a rectangular or other suitably-shaped air-heating chamber, B, which is sufficiently large to extend entirely across the throat of the fire-place in either direction, and this chamber is traversed by a central flue, C, up which all the products of combustion ascend into the chimney D. This air-heating chamber receives its supply of air through an induction pipe, E, which may either draw the air from the room in which the grate is placed, or it may communicate with the external atmosphere, and the flow of air through said pipe is regulated by a valve, e. In order to compel the air to traverse the entire interior of the chamber B, I provide it with a horizontal diaphragm, F, which extends almost the entire length of the said chamber, and as the inlet pipe E conducts the cold air in under said diaphragm, the air is thus caused to circulate through the chamber, and to become thoroughly warmed. This chamber is furnished with a door, G, which opens into the room at the side of the fire-place, and this door admits of the hot-air chamber being cleaned at any time when found to be necessary. A handle, k, which passes through this chamber, is furnished with a damper, K, for regulating the draught of the fire up the flue C. Situated a slight distance above the chamber B is a drum, L, and this drum is connected to the said chamber by means of the side or branch pipes M M', and, like this chamber, it is also provided with a central flue, N, which is coincident with the other flue C. The branch pipes M M' conduct the previously-warmed air from the chamber B into the drum L; and as this drum has an internal flue, and is also surrounded by the heated gases, &c., which are ascending within the chimney, the air is a second time heated, and it is then discharged into the room by the pipe O. The pipe O may have another exit pipe, P, attached to it, for the purpose of conducting the heated air into an upper apartment, and this latter pipe may be carried up within the chimney, if desired. It will be seen that this apparatus acts to warm and ventilate the room in the most effectual way, and with the least consumption of fuel, and the provision of the damper K enables the fire to be controlled as readily as, and with all the advantages peculiar to a stove. The flue N of the drum L may be omitted without impairing the efficiency of the apparatus to any great extent.

I claim herein as new, and of my invention—

1. The combination, substantially as described, of the heating-chamber B, internal flue C, induction pipe E, drum L, branch pipes M M', and exit pipe O, the whole being arranged and operating as herein described and set forth.

2. In combination with the elements B, C, E, L, M M', and O of the preceding clause, I also claim the diaphragm F and the damper K k, for the purpose specified.

In testimony of which invention I hereunto set my hand.

CHAS. KALBFUSS.
